(57) **CLAIM**

The ornamental design for a smoking accessory case, as shown and described.

DESCRIPTION

FIG. 1 is a front perspective view of a smoking accessory case in a closed configuration;

FIG. 2 is a front view of the smoking accessory case of FIG. 1 in a closed configuration;

FIG. 3 is a back view of the smoking accessory case of FIG. 1 in a closed configuration;

FIG. 4 is a right side view of the smoking accessory case of FIG. 1 in a closed configuration;

FIG. 5 is a left side view of the smoking accessory case of FIG. 1 in a closed configuration;

FIG. 6 is a top view of the smoking accessory case of FIG. 1 in a closed configuration;

FIG. 7 is a bottom view of the smoking accessory case of FIG. 1 in a closed configuration

FIG. 8 is a front perspective view of a smoking accessory case in an open configuration;

FIG. 9 is a front view of the smoking accessory case of FIG. 1 in an open configuration;

FIG. 10 is a back view of the smoking accessory case of FIG. 1 in an open configuration;

FIG. 11 is a right side view of the smoking accessory case of FIG. 1 in an open configuration;

FIG. 12 is a left side view of the smoking accessory case of FIG. 1 in an open configuration;

FIG. 13 is a top view of the smoking accessory case of FIG. 1 in an open configuration;

FIG. 14 is a bottom view of the smoking accessory case of FIG. 1 in an open configuration; and,

FIG. 15 is a front view of the smoking accessory case of FIG. 1 in an open configuration.

In the drawings, the claimed design is defined by the shaded surfaces; broken lines immediately adjacent shaded surfaces represent boundaries of the claim and form no part thereof; all other broken lines depict unclaimed environmental subject matter and form no part of the claim.
